(57) **CLAIM**

The ornamental design for a nail polish bottle as shown and described.

DESCRIPTION

FIG. 1 is a perspective view of the nail polish bottle of our design;

FIG. 2 is a side view of the nail polish bottle of FIG. 1;
FIG. 3 is a front view of the nail polish bottle of FIG. 1;
FIG. 4 is a side view of the nail polish bottle of FIG. 1, being the opposite side of the view shown in FIG. 2;
FIG. 5 is a rear view of the nail polish bottle of FIG. 1;
FIG. 6 is a top view of the nail polish bottle of FIG. 1; and,
FIG. 7 is a bottom view of the nail polish bottle of FIG. 1. The broken lines shown in the drawings depict portions of the nail polish bottle that form no part of the claimed design.

1 Claim, 6 Drawing Sheets
